GAS BURNER

Frank R. Higley, Cleveland Heights, Ohio, assignor to Bryant Heater Company, a corporation of Ohio

Application September 20, 1943, Serial No. 503,019

9 Claims. (Cl. 158—117)

1

This invention relates to improvements in gas burners.

The conventional gas burner consists of a gas nozzle, a mixing tube having a Venturi throat and a burner head of substantial volume in which are located a multiplicity of gas ports. The mixing chamber in such a burner is a tubular member symmetrical about an axis that passes centrally through the throat of the mixer, the cross-sectional area of the tube beyond the throat increasing with the distance from the throat. The function of the mixing tube in addition to entraining air is to convert kinetic energy at the throat into pressure energy at the burner head. The rate of flow is high at the throat, decreases in the direction of the mouth of the mixing tube, and is low in the burner head due to the large volume of the latter. The port areas of the head are relatively small, and therefore bring about an increase in the rate of flow at those points, which is essential in order to prevent backfire. In other words the rate of flame propagation at the ports must not be greater than the rate of gas flow there. Thus in the conventional system rate of flow is decreased and then again increased. The present invention is characterized by the omission of the large burner head volume, which eliminates the two last mentioned changes in rate of flow. In my invention the mouth of the mixing chamber functions as the burner port or ports and the rate of flow at the mouth becomes the rate of flow at the ports. Consequently there is no intermediate decrease in rate of flow as there is within the head of the conventional burner.

One of the objects of the invention is the provision of a burner of simplified design and low cost.

Another object is the provision of a burner having universal application regardless of variations in gas constituents or combustion chamber conditions.

Another object is the provision of a burner affording adjustability of the orifice of the gas nozzle, the volume of the mixing chamber, the area of its throat, the port area and the area of the primary air passage.

A further object is the arrangement of the controls for the foregoing adjustments in such a manner that they will be readily accessible,

2

particularly when the invention is applied to a conversion burner.

Other objects and features of novelty will appear as I proceed with the description of that embodiment of the invention which, for the purposes of the present application, I have illustrated in the accompanying drawing, in which:

Fig. 1 is an elevational and partly sectional view of a burner embodying the invention, the view being taken largely on the section line 1—1 of Fig. 2;

Fig. 2 is a plan view with parts broken away to more clearly illustrate the invention;

Fig. 3 is a detail sectional view taken substantially on the line 3—3 of Fig. 2; and

Fig. 4 is a fragmental conventionalized view corresponding to Fig. 1, showing a modification.

In carrying out the invention I provide a pair of plates of similar form and size spaced apart a short distance to constitute therebetween a gas and air passage which functions as a mixing chamber. A gas nozzle is arranged to discharge gas divergently with even distribution, and this flow of gas is directed into the mixing chamber throat formed between said plates, the term gas as herein employed referring to gaseous fuel supplied to the consumer, as distinguished from a mixture of such fuel with air. The adjacent faces of the plates may be surfaces of revolution about a common axis, and are so illustrated in Fig. 4. These surfaces may extend through 360° or through any lesser angle from a given axis which, in the illustrated case, is a line through the centers of the said plates. The gas nozzle and the said throat may be positioned centrally with respect to the mixing chamber or otherwise, and the throat may be a complete annulus or a section of an annulus, or if the perimeter of the burner is other than circular, the throat may correspond in shape to such perimeter. In any event the angular range of the nozzle is the same as that of the throat. The flow of gas from the nozzle into the throat entrains air, and the mixture is formed in the mixing chamber and burned at the perimeter thereof. The depth or thickness of a mixing chamber of this character may be relatively slight without unduly increasing the radial dimension. The effective sectional areas of the passage between plates from the inner edge to the outer edge of the passage is made to

correspond approximately with the corresponding sectional areas of a conventional mixing tube of similar capacity. For example, in the illustrated embodiment the effective sectional area at the throat is computed by multiplying the circumference of the circle through the point 26 by the distance between plates 19 and 21 at that point. Likewise the effective sectional area at the circular burner port or ports 30 is computed by multiplying the circumference of the circle of that radius by the mean distance between plates. These effective sectional areas for a burner of a given capacity correspond closely with the effective sectional areas at the throat and delivery end of a conventional mixing tube for a burner of like capacity, that is a tube that is symmetrical about an axis parallel to the direction of flow, as distinguished from the mixing chamber of the disclosed structure which is symmetrical about an axis perpendicular to the flow of mixture therethrough. The passage for air and gas decreases in effective sectional area throughout the air induction portion thereof, or until it reaches the throat 26 and thereafter, because of the ever increasing circumference, it increases in effective sectional area until it reaches the perimetrical extremities of the discs and the burner port or ports 30, just as in the conventional mixing tube the passage decreases in cross-sectional area until the throat of the Venturi is reached, after which the area increases steadily toward the burner head. While in most applications of the invention I prefer that the plates making up the mixing chamber shall be flat circular disks or annular plates, I desire it to be understood that conical or dished plates are within the purview of the invention.

In the drawing I have illustrated an application of the invention to a conversion burner, wherein 10 represents a spider having a hub 11 and three evenly spaced radial arms which carry supporting posts 12. Each of these arms preferably has an extension in which is mounted a screw 13 adapted to bear upon a suitable supporting surface, indicated at 9. The hub 11 has an axial bore 14 therethrough with which a gas supply pipe 15 communicates, but the hub also has flat walls 8, one of which may be drilled and threaded for the reception of a laterally extending gas pipe instead of the axial pipe 15, when of course the lower end of bore 14 will be closed with a threaded plug. In the upper portion of bore 14 I mount an externally threaded gas tube 16 which may be rotated for the purpose of adjusting it up and down.

Each of the posts 12 carries a stud or screw 17 which is surrounded by an annular spacer 18 with a smooth bore upon the top of which rests a circular disk 19, the studs 17 being headed as shown to prevent dislocation of the disk. The lower part of each spacer is formed as a hex 20 in order that it may be turned by a wrench. Above the hex the spacer has a somewhat reduced circular section which is externally threaded. The threaded portions of these spacers extend through holes in a lower disk 21. This disk is preferably sheet metal and its holes fit snugly the threads of spacers 18 so that when the latter are turned the disk 21 moves upwardly or downwardly as may be desired.

Disk 19, which is preferably a casting, may be formed on its under surface with a series of radial corrugations 23 which taper inwardly. The angle between corrugations is 60°, so that the space enclosed between two adjacent cor-

rugations is an equilateral triangle. Thus there is provided between adjacent corrugations a maximum space for a given surface area.

The lower disk 21 has a central opening 24 in an anticlastic portion of the disc for the admission of primary air, and around this opening the disk is flared downwardly as shown at 25. An annular throat similar in function to a Venturi throat is formed between the two disks at the radial point indicated substantially at 26 in Fig. 1. This throat therefore is elongated in a circular direction about the axis of the discs. The flare of the throat 26 inwardly is in a downward direction, while its flare outwardly from the throat is in a horizontal direction. The passage between the disks outwardly of this annular throat serves as a mixing chamber 27 with an annular mouth at the periphery thereof. The disk 21 may slope upwardly toward its periphery to a slight extent in order to compensate for the additional space resulting from the tapering corrugations, and thus maintain the effective or mean depth of the mixing chamber substantially the same throughout its extent.

The upper end of gas tube 16 is machined to present an edge of uniform thickness, and this edge is caused to approach quite closely the under surface of disk 19, whereby an annular gas nozzle 28 with a narrow orifice is presented. Gas is thus caused to flow radially outward in all directions in a thin sheet. This sheet of gas in passing through the throat 26 into the mixing chamber 27 entrains primary air entering through the opening 24, and the air and gas are diffused and mixed together in the chamber 27. The mouth of the mixing chamber functions as the fuel port, marked 30 in the drawing.

Suitable means are provided for turning the threaded gas tube 16 in the hub 11 of the spider 40 in order to adjust the tube for regulating the orifice of the nozzle 28. One convenient means for this purpose, accessible from the top of the burner, consists of an axial post 31 with a screwdriver slot in its upper end and a bifurcated lower end straddling a pin 32 which is mounted diametrically in the tube. This post is journaled in a smooth hole through disk 19 so that it may be rotated to turn the tube 16. Its upper end is threaded to receive a lock nut 33.

A dished deflector 34 is threadably mounted on the tube 16, by which means its height may be adjusted to regulate the amount of air permitted to enter the burner through the opening 24. Nut 35 threaded on the tube 16 below the deflector serves as a lock nut to maintain the deflector in adjusted position.

When the burner is to be used in a furnace I find it advantageous to provide the disk 19 with an upstanding peripheral flange 36. This flange not only strengthens the disk 19, preventing breakage in handling and warpage in use, but also serves as a retainer for the lower end of a cylindrical baffle 37. The surface 9 upon which the burner is supported preferably has a circular opening 38 therethrough, concentric with the burner axis, through which air may flow. The size of this opening is such as to insure an adequate supply of primary air flowing around the periphery of the deflector 34 and through opening 24 into the throat 26, while providing at the same time sufficient secondary air at the periphery of the burner. The pattern of flame when the disk 21 is spaced from the disk 19, as in the drawing, is somewhat as shown in

70

Fig. 2, where 40 indicates the tips of the flames which are opposite the spaces 28 between corrugations, while 41 indicates the low points of the flames opposite the points of the corrugations. The height of these low flame points may be caused to approach zero as the two disks are brought closer and closer together. In any case the flame pattern permits secondary air to rise between flame points 40.

The members 19 and 21 are preferably substantially flat surfaces of revolution as shown in the drawing, but it is within the spirit of the invention to form them otherwise, that is, with their opposed faces as other surfaces of revolution. Thus the mixing chamber instead of being a flat annulus may be an annulus of conical or dished contour.

The operation of the burner will be apparent to those skilled in the art. It will be observed that a comparatively small number of parts are required and that sheet metal parts of low cost enter into the construction. The orifice of the nozzle 28 is readily adjustable for best results with different gases, and it is self-cleaning by the simple expedient of temporarily lowering the tube 18. The port area of the burner may also be regulated by manipulation of the spacers 20, and as the port area is changed in this way the area of the throat 26 and the volume of the mixing chamber are correspondingly changed.

Having thus described my invention, I claim:

1. In a gas burner of the character described, two spaced plates of similar contour and size forming a passage for gas and air, one of said plates being continuous and the other having an opening therethrough, a tubular gas conductor extending centrally through said opening and having an open end closely adjacent said continuous plate and forming therewith a nozzle having an annular orifice, said passage having a throat between said plates outwardly of said opening through which gas from said nozzle flows to entrain primary air entering the burner from said opening.

2. In a gas burner of the character described, two spaced plates of similar contour and size forming a passage for gas and air, one of said plates being continuous and the other having an opening therethrough, a tubular gas conductor extending centrally through said opening and having an open end closely adjacent said continuous plate forming therewith a nozzle having an annular orifice, said passage having a throat between said plates outwardly of said opening through which gas from said nozzle flows to entrain primary air entering the burner from said opening, and means for effecting relative adjustment between the continuous plate and the open end of said gas conductor.

3. In a gas burner of the character described, two spaced plates of similar contour and size forming a passage for gas and air, one of said plates being continuous and the other having an opening therethrough, a tubular gas conductor extending centrally through said opening and having an open end closely adjacent said continuous plate forming therewith a nozzle having an annular orifice, said passage having a throat between said plates outwardly of said opening through which gas from said nozzle flows to entrain primary air entering the burner from said opening, and means extending through said continuous plate for moving said tubular conductor toward and away from the plate.

4. In a gas burner of the character described,

two spaced plates of similar contour and size forming a passage for gas and air, one of said plates being continuous and the other having an opening therethrough, a tubular gas conductor extending centrally through said opening and having an open end closely adjacent said continuous plate and forming therewith a nozzle having an annular orifice, said passage having a throat between said plates outwardly of said opening through which gas from said nozzle flows to entrain primary air entering the burner from said opening, said tubular conductor being threadably mounted and being adapted to be turned in its mounting, whereby its open end is caused to approach or recede from said continuous plate.

5. In a gas burner of the character described, a pair of spaced plates of similar contour and size forming a passage for gas and air, one of said plates having an opening therethrough, said passage having a throat surrounding said opening and having its mouth at the perimeter of the plates, gas nozzle means arranged to discharge gas radially through said throat to entrain air entering the burner from said opening, and a plurality of supports for both of said plates intermediate said throat and mouth, said supports comprising means for varying the spacing of said plates.

30 6. In a gas burner of the character described, a pair of spaced plates of similar contour and size forming a passage for gas and air, a plurality of supports on the inner side of the passage, a perforated spacer on each of said supports 35 against which the outer plate bears, each of said spacers being threadably mounted in a hole extending through the inner plate, a stud mounted in each support extending through the corresponding spacer and through a hole in the outer plate, said spacers being rotatable about said studs for moving the inner plate toward and away from the outer one.

7. In a gas burner of the character described, 45 a pair of spaced plates of similar contour and size forming a passage for gas and air, supporting means, one of said plates being continuous and the other having an opening therethrough, a tubular gas conductor mounted in said supporting means extending through said opening 50 and having an open end closely adjacent said continuous plate and forming therewith a nozzle having an annular orifice adapted to discharge gas radially into said passage to entrain air entering the burner through said central opening, 55 said gas conductor and said continuous plate being relatively adjustable toward and away from each other for regulating the nozzle orifice and one of said plates being adjustable on said supporting means for varying the spacing of the plates.

8. In a gas burner of the character described, 65 a pair of spaced plates of similar contour and size forming a passage for gas and air, supporting means, one of said plates being continuous and the other having an opening therethrough, a tubular gas conductor mounted in said supporting means extending through said opening and having an open end closely adjacent said 70 continuous plate and forming therewith a nozzle having an annular orifice adapted to discharge gas radially into said passage to entrain air entering the burner through said central opening, said continuous plate being fixed with respect to said supporting means, said gas conductor

being adjustably mounted in said support for regulating the nozzle orifice, and the other plate being adjustable on said supporting means toward and away from the fixed continuous plate.

9. In a gas burner of the character described, a pair of spaced plates of similar contour and size with a passage therebetween, one of said plates being continuous and the other having a circular opening therethrough for the admission of primary air, a gas tube axially arranged with respect to said opening having an open end closely adjacent to said continuous plate, forming therewith a nozzle with an annular orifice through which gas may be discharged radially into said passage to entrain air entering the burner from said opening, means for adjusting said tube axially, and a shutter adjustably mounted on said tube for regulating the air flow through said opening.
